UNITED STATES PATENT OFFICE.

HENRY G. MORRIS AND PEDRO G. SALOM, OF PHILADELPHIA,
PENNSYLVANIA.

DESIGN FOR A VEHICLE-BODY.

SPECIFICATION forming part of Design No. 26,524, dated January 12, 1897.

Application filed September 30, 1896. Serial No. 607,502. Term of patent 14 years.

To all whom it may concern:

Be it known that we, HENRY G. MORRIS and PEDRO G. SALOM, citizens of the United States, and residents of Philadelphia, Pennsylvania, 5 have invented a certain new and useful Design for a Vehicle-Body, of which the following is a specification.

Our design for a carriage-body is fully illustrated in the accompanying drawings, in 10 which—

Figure 1 is a side view, and Fig. 2 is a plan view.

The essential features of the design are the rearwardly-projecting portion back of the 15 main body of the carriage and the operator's seat mounted thereon.

A is the main body of the carriage, having the seat portion a and the hood a^2 and the floor-section a' .

B is a rearwardly-extending quadrangular 20 section, and mounted on this section is a seat-section E, the whole combined giving the effect as shown in the accompanying drawings.

We claim—

The design for a carriage-body as herein described and as shown in the accompanying 25 drawings.

In testimony whereof we have signed our names to this specification in the presence of two subscribing witnesses.

HENRY G. MORRIS.
PEDRO G. SALOM.

Witnesses:

WILL. A. BARR,
JOS. H. KLEIN.
